UNITED STATES PATENT OFFICE.

CHARLES G. HOLMES AND ARTHUR E. HOLMES, OF MILWAUKEE, WISCONSIN, AS
SIGNORS TO RACINE FURNACE & FOUNDRY CO., A CORPORATION OF WISCONSIN.

FURNACE GRATE.

Application filed June 18, 1921. Serial No. 478,589.

To all whom it may concern:

Be it known that we, CHARLES G. HOLMES and ARTHUR E. HOLMES, citizens of the United States, and residents of Milwaukee, in the county of Milwaukee and State of Wisconsin, have invented new and useful Improvements in Furnace Grates, of which the following is a description, reference being had to the accompanying drawings, 10 which are a part of this specification.

This invention relates to improvements in furnace grates, and particularly to grates having rotary grate bars.

The invention has for an object to provide a simple and durable grate and grate shaking mechanism in which the successive operations of the shaking mechanism will rotate the individual grate bars in one direction, and in which adjacent bars will be 20 rotated in opposite directions.

A further object is to provide a grate construction in which an individual grate bar may be removed and replaced without disturbing the other bars.

25 A still further object is to provide a simple and durable mechanism for converting the reciprocating movement of the shaker lever into the rotary motion of the grate bars.

30 The invention consists in the novel constructions, arrangements and combinations, to be hereinafter described and claimed for carrying out the above stated objects and such other objects as will appear from the following description of a certain preferred embodiment illustrated in the accompanying drawings, wherein—

Fig. 1 is a plan view of the grate, a part of the casing having been broken away to 40 show the shaking mechanism;

Fig. 2 is a front elevation, the casing having been removed to show the shaking mechanism.

Fig. 3 is a vertical section taken along the line 3—3 of Fig. 1, certain of the parts having been broken away; and

Fig. 4 is a detail section showing a bar supporting hook, taken along the line 4—4 of Fig. 3.

50 Like characters of reference designate like parts in the several figures of the drawings.

In the drawings, 10 designates a furnace casing having a portion 11 projecting from the furnace proper to house the shaking

mechanism 12. Within the fire box 13 are disposed a plurality of grate bars 14, having a number of spaced triangular flanges 15. When the invention is employed in connection with a circular fire box, as shown, the bars vary in length, as illustrated. The remote ends of the bars are supported within bearing projections 16 extending from the fire box wall. The ends 17 of the grate bars are circular in cross-section, and fit within the bearing projections. 65

The opposite ends of the bars are supported within bearings comprising an upper fixed bar 18 having bearing recesses 19 therein, and a lower removable bar 20 having bearing recesses 21 therein. The bar 20 is provided at one end with a hook 22 adapted to hook over a hook 23 on the casing. The other end of the bar is perforated and is supported between perforated lugs 24 by means of a pin 25. Cotter keys 26 or other suitable means, are employed to hold the pin 25 in place, but at the same time permitting its removal in order to lower the bar 20 for the purpose hereinafter pointed out. 70

Adjacent their forward ends the grate bars are provided with portions 27 rectangular in cross section adapted to fit within gears 28 having corresponding squared openings. The gears 28 are designed to mesh with adjacent gears, as illustrated. 75 Certain of the bars are provided with shoulders 29 to properly position the gears. The center bars are provided with elongated squared portions 30 for the purpose of strength, and the gears 28 fitting over 80 these bars are provided with elongated hubs 31 fitting over these squared portions. Suitable shoulders 32 on these bars serve to align the gears. 85

One of the center bars is provided with a pair of spaced discs 33, suitably secured to the hub of the gear so as to transmit rotation thereto. A plurality of pins 34 corresponding in number to the number of faces to the members 15 are placed equi-distantly 90 apart between the discs 33. As illustrated, three pins are employed. These pins are so positioned that when the shaking mechanism, hereinafter described, operates to rotate the bars, the rotation of each of the bars will be halted so that one of the flat surfaces of each member is uppermost, thus forming the bed of the grate. As illustrated 95 100 105

these pins are in substantial longitudinal alignment with the apexes of the triangular elements.

The shaking mechanism comprises a shaking lever 35 pivoted at its lower end at 36 to the casing of the furnace, and having also pivotally connected thereto intermediate its ends, a link or connecting rod 37. The connecting rod 37 is provided with a cross head 38 adapted to slide between guides 39. Connected with the cross head 38 is a link 40 which in turn is pivoted to a swinging arm 41 at 42. The swinging arm 41 is pivoted to the casing of the furnace at 43. Suitable stops 44 are provided to limit the oscillation of the arm 41 and in turn the movement of the shaking lever in rotating the grate bars. Pivoted to the opposite end of the arm 41 is a pawl 44' having a hooked end 45 adapted to hook over the individual pins 34. The end 46 of the pawl is provided with an inclined surface 47 to permit it to travel over the pins when moving in the opposite direction. Movement of the shaking lever toward the left as viewed in Fig. 3, causes the pawl 44' to move to the left from the position illustrated in Fig. 2, and to rotate the bars a third of a rotation, and thus bring the succeeding flat surfaces of the members 15 into position. Alternate grate bars rotate in the same direction. The reverse movement of the shaker lever causes the pawl to travel in the opposite direction and finally to engage the succeeding pin 34. It will be noted that each individual grate bar always rotates in one direction. One of the stops 44 prevents the grate bars from being rotated too far beyond the proper position.

In order to remove an individual grate bar for any reason, the cotter pins 26 are removed to permit the withdrawal of the pin 25. This permits the lowering of the lower bearing bar 20. In order to prevent the grate bars from falling out of place when the bar 20 is lowered, hooks 48 project from the furnace casing, and extend partially around the individual grate bars to hold them in place. These hooks are designed so as to extend somewhat below the normal

position of the grate bars when in place, so as not to serve as a bearing. In other words, in normal operation the grate bars are raised slightly out of contact with the hooks 48. The grate bar desired to be removed may be disengaged from the hook and dropped to the bottom of the furnace. The bar may be withdrawn from its bearings 16 by pulling it forward. A new grate bar may be inserted in place without disturbing the arrangement of the other bars, it being merely necessary to mesh the gear on the new bar properly with the adjacent gear, so that the surface of the grate will always be flat.

It will be observed that numerous changes may be made in the construction of a furnace embodying the improved grate without departure from the spirit of the invention.

I claim:

1. In a grate construction, the combination with a housing of a plurality of interconnecting grate bars pivotally mounted therein; a disc provided with a plurality of arcuately spaced pins, carried by one of said bars; a pawl reciprocable transversely of the axis of said disc, adapted to engage said pins to arcuately move said bars; an operating lever movable in a plane parallel to the axes of said bars; and operating connections between said lever and pawl.

2. In a grate construction, the combination with a housing of a plurality of interconnected grate bars pivotally mounted therein, alternate bars being simultaneously movable in opposite directions; a disc provided with a plurality of arcuately spaced pins, carried by one of said bars; a pawl reciprocable transversely of the rotative axis of said disc, adapted to engage said pins to arcuately move said bars; an operating lever pivotally carried by said housing for movement in a plane parallel to the axes of said bars; a swinging arm, one end of which is pivotally connected to said pawl; and links connecting said arm and lever.

In testimony whereof, we affix our signatures.

CHARLES G. HOLMES.
ARTHUR E. HOLMES.
